UNITED STATES PATENT OFFICE

2,625,098

MACHINE FOR MAKING AN IMPRINT ON
CYLINDRICAL ARTICLES

Charles F. Robbins and Bertrand G. Harvey,
Keene, N. H., assignors to Markem Machine
Company, Keene, N. H., a corporation of New
Hampshire

Application December 7, 1949, Serial No. 131,558

2 Claims. (Cl. 101—38)

1

This invention relates to a machine for making an imprint on a cylindrical article, and is in the nature of an improvement on the machines shown in United States Patents No. 2,459,538, January 18, 1949 and No. 2,461,233, February 8, 1949.

The machine shown in said patents comprises a printing cylinder having on its periphery printing plate carrying the type characters by which the printed impression is made on the cylindrical article, and an article holder or mask situated above the printing cylinder and having a vertical opening extending therethrough of a size to freely receive the cylindrical article to be printed, the arrangement being such that when the cylindrical article is deposited in the opening of the holder, said cylindrical article will rest on the printing cylinder with its axis parallel to that of the cylinder and at the same time will be free for rotation within the opening of the article holder so that when the printing cylinder is rotated, the article within the holder will be rotated about its axis by its frictional engagement with the periphery of the printing cylinder, and during such rotation the type characters of the printing plate will make the desired printed impression on the article.

In Patent No. 2,461,233 the printing cylinder is provided with an article-receiving cavity located at the trailing end of the printing plate so that during the rotation of the printing cylinder, said cavity will come into register with the article in the holder after the printed impression has been made thereon, and the printed article will thereupon drop out of the opening in the article holder into said cavity and will be removed from beneath the holder and discharged from the printing cylinder by further rotation of the latter.

In the devices shown in said patents it is necessary to employ an article holder with an opening which is of the proper size to receive the article to be printed, which means that if the machine is set up for printing an article of one size and it is desired to print a lot of cylindrical articles of another size, it will be necessary to exchange the article holder for another one having the opening of the proper size for the second lot of cylindrical articles. This involves, therefore, the necessity of having on hand a sufficient number of article holders having openings of different sizes to accommodate the different sizes of articles to be printed.

Moreover, experience has shown that sometimes an article becomes jammed in dropping from the article holder into the article-receiving cavity, and if the article is made of glass, this may result in a breakage.

2

It is one of the objects of our invention to provide an improved form of article holder which is readily adjustable for different sizes of articles so that by merely making a simple adjustment in the article holder, it can be used for printing articles of a wide variety of diameters or sizes.

A further object of the invention is to provide a form of article holder which obviates the danger of breakage of any cylindrical articles which are made of glass or other fragile material when said article has received its imprint and is being discharged from the machine.

In the drawings wherein we have illustrated one embodiment of our invention,

Fig. 1 is a side view of a machine embodying our invention and showing the article holder in its operative position;

Fig. 2 is a view similar to Fig. 1 but showing the article holder in raised position in which the printed article is released, said view showing the manner in which the printed article is discharged;

Fig. 3 is a front view of the machine looking toward the left in Fig. 1;

Fig. 4 is a fragmentary enlarged view of the printing cylinder and article holder looking toward the right in Fig. 1.

Fig. 5 is a fragmentary view illustrating the manner in which the article holder is adjusted for different sizes of cylindrical articles.

Fig. 6 is an enlarged section on the line 6—6, Fig. 1.

The machine herein shown comprises a suitable frame 1 in which is mounted a shaft 2 carrying the printing cylinder 3, the latter having a continuous cylindrical surface to which is secured a printing plate 4 carrying the type characters by which the desired printed impression is made on a cylindrical article which is indicated at 5. The printing plate 4 may conveniently be made of rubber and thus provided with rubber type characters.

The printing cylinder 3 is shown as provided with a pair of rings 36 between which the printing plate 4 is located, said rings constituting the supporting portion of the printing cylinder on which the cylindrical article 5 rests.

The shaft 2 may be rotated in any usual way as by means of a motor 6 which is connected to the shaft by means of suitable gearing 7.

6 indicates an ink roll operating in an ink reservoir 9 and by which the type characters are inked during the rotation of the printing cylinder 3.

Our improved article holder comprises a head member 10 from which depends two pairs of arms, the arms of each pair being indicated at

11 and 12. Each arm carries at its lower end a roller 13 and said arms 11 and 12 of each pair are so positioned relative to each other that the distance between the adjacent peripheral surfaces of the rolls 13 of each pair of arms is slightly less than the diameter of the cylindrical article 5 on which the imprint is to be made. The head 10 is yieldingly carried by a supporting member 14 which is mounted on the frame for vertical movement, said supporting member being shown as carried by an arm 15 extending laterally from a lever 16 which is pivotally mounted at 17. The supporting member 14 is provided with an interior chamber 20 and the head 10 is formed with an upwardly extending stem 18 which extends into the chamber 14, the upper end of the stem being provided with an enlarged portion 19 which prevents the withdrawal of the stem from the supporting member 14. Situated within the interior chamber 20 of the supporting member 14 is a spring 21 which exerts a downward pressure on the enlarged portion 19 of the stem and normally maintains said enlarged portion in engagement with the bottom of the chamber 20 as shown in Fig. 1.

The lever 16 is actuated by suitable cam mechanism, hereinafter described, by which said lever, the arm 15 extending therefrom, the supporting member 14 carried by the arm 15, and the roll assembly, consisting of the head 10 and the rolls 13, are given an up and down movement.

When the article holder or roll assembly is in its lowered operative position shown in Fig. 1, the rolls 13 of each pair have a straddling relation relative to a cylindrical article 5 that is in position to be printed, and said article will thereby be yieldingly held against the supporting rolls or rings 36 of the printing cylinder as shown in Fig. 1. The frictional engagement thus provided between the printing cylinder 3 and the cylindrical article 5 resting thereon is such that the rotation of the printing cylinder will rotate the article 5 about its own axis as indicated by the arrows in Fig. 1. When, during such rotation, the printing plate 4 passes beneath the cylindrical article 5, the desired printed impression will be made on said article.

The means controlling the lever 16 is such that after a printed impression has been made on any cylindrical article, the lever is raised thereby raising the article holder into the inoperative position shown in Fig. 2. When the article holder is thus raised, the printed cylindrical article 5 is released and is free to be discharged from the printing cylinder as shown in Fig. 2, this discharge being assisted by the fact that the printing cylinder is rotating counterclockwise in Fig. 1.

If desired a suitable receptacle 37 may be employed to receive the discharged printed article.

To further facilitate the discharge of the printed cylindrical article, we propose to so arrange the parts of the machine that the article holder will be offset somewhat on the discharge side of the vertical center line of the printing cylinder as best seen in Fig. 1 so that when the article holder is raised after an article has received its imprint, the discharge of the article will be assisted partly by gravity and partly by the rotative movement of the printing cylinder 3.

The means for raising and lowering the article holder herein shown is similar to that illustrated in the above-mentioned patents. The lever 16 is provided with an extension 22 which is connected by a link 23 to one end of an arm 24 of

an elbow lever 25 which is pivoted to the frame at 26, the other arm 27 of said elbow lever cooperating with a cam 28 on the driving shaft 2. Said cam has a high portion 29 which at the appropriate point in the rotation of the printing cylinder will engage the end 30 of the lever 25 thereby rocking the latter and operating through the link 23 to turn the lever 16 and raise the article holder from its operative position shown in Fig. 1 to its inoperative position shown in Fig. 2.

The cam 28 is so designed that when the end 30 of the elbow lever 25 is resting against the low portion of the cam, and the rolls 13 of the roll assembly or article holder are resting against a cylindrical article 5 that is in printing position, as shown in Fig. 1, the enlarged end 19 of the stem 18 will be spaced from the bottom of the chamber 20 and rolls 13 of the roll assembly will therefore be yieldingly held against the article 5 by the spring 21.

The machine herein shown is provided with means for automatically feeding unprinted cylindrical articles to the article holder, and for this purpose there is provided an inclined chute 31 to receive a plurality of cylindrical articles.

The construction is such that when the article holder is in its lowered position and the rolls 13 are in yielding engagement with an article 5 that is in printing position, the bottom article in the chute will engage one of the rolls 13 as shown in Fig. 1, whereby the unprinted articles will be retained in position in the chute.

When the article holder is raised into its inoperative position for the discharge of a printed article, the bottom article in the chute will then roll into position on to the printing cylinder 3 as shown in Fig. 2. The cam 28 is so designed that the upward movement of the article holder is just sufficient to release the printed article and to allow the bottom unprinted article in the chute to gravitate into position on the printing cylinder, and the return movement of the article holder from its raised to its lowered position will occur just in time to catch the article which has rolled off from the chute and retain said article in printing position.

To enable the article holder to function properly with cylindrical articles of different diameters, we propose to pivotally connect the leg 12 of each pair of legs to the head 10 as shown at 32 so that the rolls 13 of each pair of legs can be adjusted relatively toward and from each other. Each pivoted leg 12 has a link 33 connected thereto which is provided with a slot 34 that receives a clamping bolt 35 carried by the leg 11 of the pair. By loosening the clamping bolts 35, the arms 12 can be adjusted so as to properly position the rolls 13 of each pair of legs to cooperate with a cylindrical article of any one of a wide variety of different diameters.

We claim:

1. A machine for making an imprint on cylindrical articles comprising a printing cylinder having a continuous cylindrical surface carrying type elements, means to rotate said printing cylinder, article holding means above the printing cylinder for holding a cylindrical article to be printed in a position above and resting on the printing cylinder and with its axis parallel to that of the printing cylinder, said article-holding means comprising a head member, two pairs of rolls mounted on the head member with the pairs of rolls spaced from each other lengthwise of said cylindrical article and with the rolls of each

pair spaced from each other in a direction transversely of the axis of said cylindrical article a distance slightly less than the diameter of said cylindrical article, and means for moving said head member vertically between a raised inoperative position in which the rolls are located above the cylindrical article and a lowered operative position in which the rolls of each pair engage the cylindrical article in straddling relation thereto, and thereby hold it in printing position, said rolls constituting the sole means for thus holding the cylindrical article in printing position, whereby the article is released when the rolls are in their raised position.

2. A machine for making an imprint on cylindrical articles comprising a horizontally disposed printing cylinder having a continuous cylindrical surface carrying a printing member, means to rotate said printing cylinder, an article-holding means for holding a cylindrical article to be printed in a printing position above and resting on the printing cylinder and with its axis parallel to that of the cylinder, and also in a position slightly to one side of the vertical diametrical line of the cylinder, said article-holding means comprising a head member, two pairs of rolls mounted thereon and depending therefrom and with their axes parallel to that of the printing cylinder, the rolls of each pair being spaced apart a distance slightly less than the diameter of the 30 cylindrical article, and the pairs of rolls being spaced apart in a direction lengthwise of said article, means moving said head member vertically between a lower operative position in which

the rolls of each pair engage the cylindrical article in straddling relation thereto, and thereby hold it in printing position while permitting it to rotate freely by frictional contact with the printing cylinder, and a raised inoperative position in which the rolls are above and out of contact with the cylindrical article, said rolls when in their lowered position constituting the sole means for holding the cylindrical article in printing position, whereby when the rolls are raised the cylindrical article is released and because of its position at one side of the vertical diametrical line of the printing cylinder is free to roll off therefrom, and spring means yieldingly holding said rolls in contact with said cylindrical article when they are in their lower operative position.
